David Adams Richmond Virginia

Cotton Patent

The Schedule referred to in this Cotton Patent and making part of the same, containing a description in the words of the said David Adams, himself of his Improvement in the Cotton or Wool Carding Machines.

To all whom these presents shall come: Be it known that David Adams of Richmond in the County of Henrico and State of Virginia has invented a new and useful Improvement in Cotton or Wool Carding Machines & especially in Cotton Carding Machines by adding one more clapping Cylinder to said Machine in addition to the one heretofore used, whereby one half more work and of a better quality can be done by the Machine in the same time than according to its present structure & that the following is a full and exact description of the construction and operation of the said Machine as invented or improved by me of which I claim only the advantage of the newly invented or discovered part & omit the second Clapping Cylinder indicated on the drawing to which accompanies this declaration by the dotted line the principle of which will be to keep the main Cylinder more free from an overload of Cotton or Wool whereby the Machine is enabled to do one half more work & of a better quality than it can do according to its present structure. The dotted line on the said drawing is a Clapping Cylinder by which the cotton or wool is taken off the main Cylinder C. The reason of its being called the Hopper is because the Cotton or Wool being supplied to be carried at once will come to rest in the Hopper off the Cylinder C. And the single clapping Cylinder B can then take off all the Cotton or Wool off the main Cylinder that ought to be taken off but not so much that a great portion is lost by the velocity of the main Cylinder C or because not what is not so taken off by the single Hopper moves on the said drawing B to carry round again in the main Cylinder C which keeps the Cards to full that they cannot break with the ease desired. The

17689 X

mention of this incident is the addition of a lower Doffer Cylinder indicated
and marked on the drawing which accompanies the description by the letter
A, which catches & delivers a sheet of Cotton or Wool indicated on the
same drawing by the letter C and which being taken off at that particular
point is the best part of the Carding that can be made. Before the said intro-
duction of the said second Doffer the sheet of Cotton or Wool on the main Cylinder
would not be taken off in the old way of Carding. The upper Doffer B does
as much work with the lower Doffer A as it did before its addition and what
is done by the lower Doffer A is exactly so much additional work done by
the machine.

The advantages to be derived from the use of the additional Doffer
are that a carding, Wool or Cotton machine will do twice as much work
with it as it will without it - the work will be made better done there will
be much less flying or waste & it will require but a trifle more power to drive
the machine.

In testimony whereof I have hereunto set my hand and affix
my seal this 20th day of March 1832
